UNITED STATES PATENT OFFICE.

WINFRED T. POWELL, OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

MANUAL TELEPHONE SYSTEM.

Application filed March 15, 1924. Serial No. 699,575.

This invention relates to manual telephone systems and more particularly to telephone systems in which several operators cooperate in completing a telephone connection.

- 5 In inter-office telephone connections it is customary for an originating operator, known as an A operator to communicate the wanted number over an order wire to a B operator located at the distant wanted office; 10 the B operator then assigns a trunk to the A operator for extending the call. Much confusion is caused by the use of such an order wire, resulting in numerous mistakes and also resulting in the service being materially retarded.

It is the purpose of the present invention to provide an arrangement in which the order wire may be dispensed with and in which the wanted number may be recorded 20 on a register device at the originating office. This record may be transmitted over a selected trunk to an indicating mechanism at the B operator's position located at the wanted office.

- 25 The main feature of the present invention resides in the provision of means whereby the operator at the originating office, by manually closing a single pair of contacts, selectively actuates a recording device to record the designation of a telephone line indicated by a plurality of digits.

30 A further feature of the invention consists in the provision of means whereby a signaling circuit extending through a contact of a manual plug and a contact individual to the wanted telephone line, selectively controls the recording device.

- 35 Another feature of the invention consists in the arrangement of circuits whereby any one of a number of recording devices may be associated with a link circuit on the initiation of a call, and whereby the selected recording device may be actuated to record a plurality of digits corresponding to the wanted telephone line by the manual closure of a single pair of contacts.

40 The drawings, with Fig. 2 at the right of Fig. 1 and with Fig. 3 placed below Fig. 1 diagrammatically represent a portion of a telephone system, incorporating the present invention. At the left of Fig. 1 there is represented a manual telephone line terminating in a substation designated 1. This line may terminate in an answering jack at each

55 of several operators' positions, with each of which jacks there is associated a line lamp. A call to said telephone line is also completed through a multiple of one of these jacks. At the upper part of Fig. 1 there is represented one manual cord circuit of 60 which there may be a plurality at each operator's position. At the lower left hand corner of Fig. 1 and at the upper right and lower right hand corners of this figure, partially bounded by dotted lines, there is shown 65 the equipment common to a plurality of cord circuits located at the operator's position. In Fig. 3 there is shown a register sender equipment and a register controller switch, which cooperate with the receiving equipment of Fig. 2, to indicate the number of 70 the wanted line. The register sender, shown in the center and left hand portion of Fig. 3, is one of several of such sender equipments, the number of which is determined by 75 the number of calls originated simultaneously. Below the dotted line of Fig. 3 there is indicated a code machine, which is common to all of the positions in the exchange. Fig. 2 represents the equipment at 80 the "B" operator's position and at the lower right hand corner there is indicated a call indicating device preferably of the visual type, in which a series of lamps, one for each digit of the wanted number are selectively 85 lighted under the control of relays. At the lower left hand corner of Fig. 2 there is shown a progressively movable switch, which may be known as a receiver switch, 90 that cooperates in the control of the lamps and relays of the number indicated. At the upper right hand corner of Fig. 2, a party line is indicated; only one of its substations 95 is shown.

The progressively movable switches, here- 100 in referred to, may be substantially similar to that disclosed and described in the patent to Clement #1,107,153, patented August 11, 1914. The code machine shown below the dotted line of Fig. 3, is composed of 21 cams, 105 arranged to open and close circuits for actuating the register relays of the register sender, shown in the upper left hand corner of Fig. 3. The cam-actuated spring contacts as shown on this figure, may be in the form of commutators and brushes, similar to a code machine, if only they close circuits in the positions indicated in this figure.

The cams herein designated A to D inclusive, are divided into four equal sectors and the cams E to U inclusive are divided into six sectors, as shown. The positions 0 of all the cams L to U inclusive, are for the purpose of starting the registration at the beginning of the thousands digit, since it is only possible to move the register control switch out of position 1 when one of these cams is in position 0 of its first revolution. During revolutions 2, 3 and 4, cam D will open so that it will be impossible to start registering the thousands digit during the hundreds, tens or units cycles. The shaft controlling cams A, B, C and D is geared to the shaft controlling cams E to U inclusive, in a one to four ratio, that is, for each revolution of the long shaft having a larger number of cams, the short one moves its small number of cams through one of its four cycles.

At the upper right hand corner of Fig. 3 there are represented two terminals 39 and 133, and these terminals may be in the form of pins or other contacts that may be easily touched by the tip contact of a plug. At each operator's position of a ten thousand line system, there are provided ten thousand of these contacts such as 39 and 133, arranged in a compact contact bank, one of which is provided for each operator's position. The contact such as 39, which is individual to a subscriber's telephone line is multiplied throughout the contact banks at several operators' positions, much after the manner in which multiple jacks are now wired in the present telephone switchboards. Although it has been stated that a set of these terminals is provided for each operator, it will be understood that a set of terminals may be provided for a plurality of operators, provided of course that a contact bank is within easy reach of all of the operators.

It is believed that the invention would best be understood by describing the method of establishing a telephone connection from a substation, such as indicated at 1 located in one office, to a wanted telephone line 2, terminating at a second or distant office. When the subscriber at 1, originates a call by removing his receiver from its switchhook, the line relay 2 is operated over the two sides of the calling line in series and attracts its armature to light the line lamp 4. The operator on noting that the lamp 4 is lighted inserts the plug 5 into the jack 6 of the calling line, whereupon the relay 7 is operated from grounded battery, its left hand high resistance winding, sleeve contacts of the plug 5 and the jack 6, winding of the cut-off relay 3 to ground. The cut-off relay is also energized in this circuit and at its armatures and back contacts opens the mentioned circuit of the line re-

lay, causing this last named relay to de-energize and extinguish the line lamp 4.

The relay 7 when energized in series with the relay 3, attracts its armatures, and at its inner right hand armature and front contact closes a locking circuit for itself through its low resistance right hand winding, its mentioned armature and front contact over the circuit previously described as extending through the winding of the cut-off relay 3. It will be noted that the relay 7 was initially energized through its high resistance winding and is thereafter held operated through its right hand winding. This arrangement prevents more than one operator from simultaneously being telephonically connected to the calling line. This is due to the fact that if a second answering plug similar to 5 is connected to a multiple jack of the calling line, the high resistance winding of the relay such as 7, of the second cord circuit will be connected in multiple with the low resistance winding of the relay 7 of the first cord circuit. The result is that the second mentioned relay 7 does not operate.

As soon as the answering plug 5 has been connected to the calling line, the answering supervisory relay 8 is energized in a circuit including both sides of the answering end of the cord circuit and both sides of the calling line. This operates the relay 8 and prevents the lighting of the answering supervisory lamp 9 at this time. As soon as the relay 8 is operated a circuit is closed from grounded battery through the high and low resistance windings in series of relay 10, back contact and armature of relay 11, left hand armature and front contact of the supervisory relay 8, back contact, continuity spring and winding of slow releasing relay 12, inner back contact and armature of relay 13, conductor 14, inner left hand front contact and armature of relay 7 to ground.

The relay 12 does not operate in series with the high resistance winding of relay 10, but the relay 10 is operated in the last described circuit and at its inner armature and front contact, closes a circuit independent of its high resistance winding. The relay 12 does operate in series with the low resistance winding of relay 10 and when operated, closes a locking circuit for itself from grounded battery, winding of relay 11, armature, continuity spring and winding of relay 12, inner back contact and armature of relay 13, conductor 14, to ground at the armature and front contact of relay 7. The relay 11 opens the circuit of relay 10, which relay is common to all of the cord circuits of a position and thus insures that the operator's head set will not be simultaneously connected to a second cord circuit.

During the time that the slow releasing

relay 10 is operated, the slow releasing operator's cut-in relay 15 is short-circuited by a circuit completed through the meter cut-off key 16, make contacts of relays 10 and 12. After the relay 11 opens the energizing circuit of the relay 10, this last named relay deenergizes and when it opens the last mentioned short-circuit effects the operation of relay 15. The energizing circuit of relay 15 is from grounded battery, its winding, innermost front contact of relay 12, and winding of position meter 17 to ground. Relay 15 is thus operated and at its front contacts and armatures connects the operator's telephone set to the calling telephone line. At this time the supervisory lamp 9 is dimly lighted to indicate to the operator to which cord circuit her telephone set is connected. The circuit for dimly lighting the lamp 9 extends from grounded battery, through the lamp, the left hand front contact and armature of relay 8, inner armature and back contact of relay 18, innermost front contact and armature of the relay 12, and winding of the position meter 17 to ground.

An idle register sender such as indicated in Fig. 3, is connected to the cord circuit taken for use as soon as the relay 12 is operated. This selection is effected by the operation of the motor magnet 19 in a circuit closed from grounded battery, winding of this magnet, its back contact and armature, outermost front contact and armature of relay 12, innermost back contact and armature of relay 20, test brush 21 and test terminal 22 and through a multiple terminal similar to 22, through an armature and front contact to ground at a relay similar to 20, at another cord circuit that has seized the register sender associated with the test terminal. Under control of this and similar circuits which indicate busy register senders, the motor magnet 19 advances the brushes of the register selector until an idle register sender is located. This condition is indicated by the absence of ground on a test terminal such as 22.

During the time that the register selector has been testing busy senders the relay 20 is short-circuited, but when an idle sender is located the relay 20 energizes and a circuit is completed from ground, its winding, middle armature and front contact of relay 12, armature, back contact and winding of the motor magnet 19 to grounded battery. The relay 20 on operation, at its inner right hand front contact and armature applies a busy potential to test terminals 22 to prevent the seizure of this selected register sender and closes a circuit for operating the relay 48 of Fig. 3.

The operator on being connected to the calling telephone line asks the number of the wanted telephone line and on learning

that this wanted telephone line terminates at a distant office, or the same office, depresses one of the office keys shown in the lower right hand corner of Fig. 1.

Let it be assumed that the operator depresses key 23. This effects the operation of relay 24 from grounded battery, its winding, contacts of key 23, conductor 25, outer right hand armature and front contact of relay 20, lowermost back contact and armature of relay 13, innermost back contact and armature of relay 26, to ground. Relay 24 on operation closes a locking circuit for itself through its right hand front contact and armature, over the remainder of the circuit just described, to ground over conductor 25. At the innermost armature and front contact of relay 24, a circuit is closed from ground, conductor 28, back contact, continuity spring and winding of relay 29, conductor 30, middle armature and front contact of relay 12, back contact, armature and winding of motor magnet 19 to grounded battery. The relay 29 energizes and closes a locking circuit for itself through its inner armature and continuity spring, which circuit is independent of the contacts of the relay 24. At the upper front contacts and armatures of relay 29, the register sender is connected to the calling end of the cord circuit.

It will be noted that the locking circuit of the office relay such as 24, is controlled through back contacts of relays 13 and 26, so that when the calling plug is inserted in the trunk jack resulting in the operation of the relay 13, the operated office relay is released. Also if an office key is accidentally operated when a calling line is not connected to the operator's telephone set, no operation of an office relay is effected. In case the operator depresses the wrong office key by mistake she may release the operated office relay by operating the release key 37, after which the proper office key may be operated. On the other hand if the registering or sending apparatus fails to operate, the operator may depress the release key and connect calls through her position by inserting the called plug into the trunk jack and passing the call orally over the selected trunk. Under such a condition the relay 29 is not operated and the tip and ring conductors are not disconnected from the cord circuit.

After selecting the proper office, the operator holds the tip 38 of the calling plug in contact with the pin terminal 39 of the wanted line. It is assumed that the designation of the wanted line is #4468, which is represented by one of the terminals 39, shown in the upper right hand corner of Fig. 3. With the tip of the plug in engagement with the terminal 39, a circuit is closed from ground, winding of relay 40, register

controller brush 41 in its first position, conductor 42, selector brush 54, conductor 53, outermost armature and back contact of relay 26, conductor 48, uppermost front contact and armature of relay 29, tip contact 38, pin contact 39 (Fig. 3), right hand armature and back contact of relay 31, outer right hand armature and back contact of relay 32, right hand winding of relay 31, conductor 44, contacts of cam S, contacts of cams D and F to grounded battery.

If the code machine is in any other position except the 0 position, the above circuit is not completed to battery; it will be open or else connected to ground so that it is not effective to operate the relay 40. When, however, the mentioned circuit is completed to grounded battery, relay 31 is operated and closes a locking circuit for itself from ground through its left hand armature, front contact and left hand winding, conductor 45. A cam contacts to grounded battery. Relay 40 does not operate in series with relay 31, but as soon as relay 31 is operated it extends the previously described test circuit to the pin terminal 39 by way of the right hand armature and front contact of relay 31, inner armature and back contact of relay 32, conductor 46, cam contacts O, D and F to grounded battery. Relay 40 is energized in this circuit and closes an operating circuit from ground, its armature and front contact, register controller brush 47, in its first position, right hand armature and front contact of relay 48, back contact, armature and winding of the motor magnet 49 to grounded battery. This operating circuit actuates the motor magnet to advance the brushes 41, 47, 49 and 50 into their second position. Relay 31, at its left hand armature and front contact also closes a circuit through the right hand winding of relay 32, but this relay does not operate until cam contacts C are closed, which is at the beginning of the second revolution of the cams E to U inclusive.

When the code machine rotates from the position 0, cam F disconnects battery and cam G connects ground to the cams H to U inclusive. The circuits are now in condition for recording the thousands digit, which in this instance is #4, and it is necessary to actuate the relay 36 of the thousands relay register to store this designation.

With the register controller in position 2 and with the cams E to U inclusive, in position 1, the registration of the thousands digit is effected. The cams H, I, J and K, are those directly used to operate the thousands register relays and in this position cam H closes its contacts, but the cam contacts O are open so that the relay 52 is not operated and the circuit through cam contacts H is therefore ineffective to operate any thousands register relay. While the

code machine passes through positions 2 and 3, cams I and J close their respective contacts, but as cam contacts O are open in these positions, the relay 52 is not energized, with the result that relays 33, 34 and 35 of the thousands register remain in their normal position. When, however, the code machine enters position 4, cam contacts O are closed and a circuit is established from ground, cam contacts G, cam contacts O, back contact and armature of relay 32, front contact and armature of relay 31, pin terminal 39, tip contact 38, upper armature and front contact of relay 29, conductor 43, outermost back contact and armature of relay 26, conductor 53, selector brush 54, conductor 42, controller brush 41 in its second position, winding of relay 52 to grounded battery. Relay 52 is energized in this circuit and attracts its armatures. This last operation closes a circuit from ground at cam contacts G and K, conductor 55, innermost front contact and armature of relay 52 through the upper winding of relay 36 to grounded battery. The relay 36 when operated closes a locking circuit for itself through its lower winding, front contact and armature to ground through the controller brush 49.

The code machine now rotates to position 5, where it completes a circuit from ground, cam contacts E, conductor 61, register controller brush 47 in position 2, right hand front contact and armature of relay 48, back contact, armature and winding of motor magnet 49 to grounded battery. This circuit causes the motor magnet to advance the controller brushes into position 3. When the code machine rotates to the 0 position, which is the start of the second cycle, cam contacts D open and cam contacts B and C are closed. The contacts C extend grounded battery from cam contacts F, conductor 56, right hand winding of relay 32, left hand front contact and armature of relay 31 to ground. Relay 32 is operated in this circuit and locks itself operated from ground at its left hand armature, front contact and its left hand winding, conductor 58, cam contacts B to grounded battery.

The test circuit extending through the pin terminal 39 is now switched from the thousands to the hundreds register, which in the case assumed is to record the hundreds digit #4. Since cam contacts D are open, cam contacts O are not connected to battery during this cycle of the machine. Cam contacts O remain open during the rotation of the machine through positions 1, 2 and 3, so that the relay 59 is not operated during that period. When, however, the O cam is rotated to position 4, its contacts are closed to complete a circuit from ground, at cam contacts G, cam contacts O, conductor 60, front contacts and armatures of relays 32 and 31, over the test circuit including the tip contact

38 and the conductors 53 and 42, controller brush 41 in its third position, winding of relay 59 to battery. The operation of relay 59 advances the controller brush into position 4. The relay 59 is not disconnected from the controller brush 41 in its 4th position, so that it remains energized. At this time, a circuit is again closed from ground at cam contacts K, conductor 55, innermost 10 front contact and armature of relay 59, winding of relay 36^A to grounded battery. Relay 36^A is operated in this circuit and closes a locking circuit for itself through its lower winding, front contact and armature to ground at controller brush 49. In 15 position 5 of the machine, cam contacts E close a circuit from ground, conductor 61, controller brush 47 in its fourth position, right hand front contact and armature of relay 48, back contact, armature and winding of the motor magnet 49 to grounded battery. The motor magnet then advances the controller brushes into their fifth position. At the close of this cycle of operation of the code machine, the cams on the long shaft move to position 0 and since this is the beginning of the third cycle of operation, the group of cams on the short shaft move to position 3, in which position cam 20 A disconnects battery from conductor 45. This permits the relay 31 to release.

The test terminal 39 is now effective to cause the registration of the tens digit since the relay 31 is in its retracted position. It is assumed that the tens digit is #6. In order to effect the registration of this digit, it is necessary to operate tens relays 33^B and 35^B. Cam Q is not effective in its 0 position to complete any circuit, but in position 1 and 3 ground at cam contacts G is extended by way of cam contacts Q and the register controller brush 41 in position 5 to operate the tens relay 63. This last named relay now closes a circuit for advancing the controller switch to position 6, where relay 63 is still maintained actuated. This advancing circuit extends from grounded battery, winding of the motor magnet 49, its armature and back contact, armature and front contact of relay 48, controller brush 47 in its fifth position, right hand front contact and armature of relay 63, to ground. While the cam contacts Q are closed in 1, the tens register relay 33^B is operated in a circuit closed from ground at cam contacts G, cam contacts H, conductor 64, outermost front contact and armature of relay 63, upper winding of relay 33^B to grounded battery. This relay on operation locks itself in 25 this condition through its lower front contact and armature to ground at controller brush 49. While the cam Q is rotated through positions 2 it opens a circuit which has been energizing relay 63, so that this relay deenergizes. But when the cam contacts Q are closed in 3, the relay 63 is again operated, in which condition it operates the tens register relay 35^B in a circuit traceable from grounded battery, upper winding of this relay, armature and front contact of relay 63, conductor 65, cam contacts J and G to ground. Relay 35^B on operation locks itself over the holding conductor to ground at controller brush 49. In position 5 the cam contacts E are closed to complete a 75 circuit from ground over conductor 61, controller brush 47 in its sixth position, right hand front contact and armature of relay 48, back contact, armature and winding of the motor magnet 49 to grounded battery. 80 This circuit advances the controller brush into position 7.

The group of cams on the long shaft now rotates into position 0 and since this is the beginning of the fourth cycle, the group of cams on the short shaft move to position 4. In this position cam B disconnects battery from conductor 58 which causes the relay 32 to release. The test conductor completed through the plug contact 38 and the pin terminal 39 is now effective to register the units digit which is #8. At this time the relays 31 and 25 90 95 32 are inactive. In order to register the units digit #8, it is necessary to operate relays 33^C, 34^C and 35^C. While the cam G is passing through positions 1, 2 and 3, a circuit is closed from ground to cam contacts S, conductor 44, right hand winding of relay 31, right hand back contact and armature of relay 32, back contact and armature of relay 31 and thence over the test circuit including the pin terminal 39, tip contact 38, of the plug, thence over conductors 53 and 42, controller brush 41 in its seventh position, winding of relay 66 to grounded battery. Relay 31 is marginal and therefore does not operate in series with the high resistance winding of relay 66. Relay 66 does energize and on energization operates the motor magnet 49 100 to advance the controller brushes into position 8. With the relay 66 operated, while the cam contacts H are closed in position 1, the relay 33^C is operated from grounded battery, winding of this relay, outermost armature and front contact of relay 66, conductor 64, cam contacts H and G to ground. Relay 33^C on operation locks itself in this condition over the holding conductor to ground at the controller brush 49. With the relay 66 still operated, the closure of its circuit to cam contacts S in positions 2 and 3, causes the relay 34^C to be operated from grounded battery, its upper winding, front contact and armature of relay 66, conductor 67, cam contacts I and G to ground. Similarly, the relay 35^C is energized from grounded battery its upper winding, armature and front contact of relay 66, conductor 65, cam contacts J and G to ground. Relay 35^C also locks 115 120 125 130

itself operated to ground at controller brush 49. When the cam E closes its contacts again it completes a circuit over conductor 61, controller brush 47 in position 8, front contact and armature of relay 48, back contact, armature and winding of motor magnet 49 to grounded battery. This causes the motor magnet to advance the controller brush into position 9.

10 The registers are now set to record the number of the wanted telephone line and a circuit is now established for lighting the office lamp, which is a visual indication to the "A" operator that the plug may be removed from the test or pin terminal and inserted in the trunk jack. The operations of recording the wanted line designations, although the description has been rather lengthy, require but a very brief interval of time.

15 The number of the wanted line has thus been recorded on the register sender and since the register controller is in position 9, a circuit is now completed from grounded battery, winding, armature and back contact of the motor magnet 49, right hand armature and front contact of relay 48, brush 47 in position 9, register selector brush 68, conductor 69, lowermost armature and front contact of relay 29, outer front contact and armature of relay 24 and office lamp 27 to ground. The lighting of the office lamp is an indication that the number is properly recorded, so that the operator now inserts 20 the calling plug of the cord circuit taken for use into the jack, such as 70, of the trunk leading to the wanted office. This operation closes a circuit from ground through the visual signal 71 and the sleeve contacts of the jack and plug just referred to, continuity spring and back contact of relay 13, winding of the slow releasing relay 26, to grounded battery. This operates the relay 26 to place the master keys shown in the upper right 25 hand corner of Fig. 1, in condition to selectively operate the frequency current selecting relays 72 and 73, shown on the lower left hand side of Fig. 3.

30 When the operator depresses a ringing key, such as 74, the slow releasing relay 75 controlled thereby is operated. This results in the energization of the slow releasing relay 13 in a circuit extending from grounded battery, lower winding of the relay 13, right hand front contact and armature of relay 26, inner front contact and armature of relay 75 to ground. The relay 13 when thus operated closes a locking circuit for itself through its upper armature and continuity spring to ground through the sleeve contacts of the plug and jack. With the relays 26 and 75 actuated, a circuit is closed from ground, outer armature and front contact of relay 75, outermost contact and armature of relay 26, conductor 53, selector brush 54,

conductor 42, controller brush 41 in its ninth position, conductor 76, winding of relay 72 to grounded battery. The frequency selecting relay 72 is thus operated and locks itself actuated in the common locking circuit completed to ground at controller brush 49. If ringing key 77 had been depressed then circuits would have been completed for operating both of the ringing frequency selecting relays 72 and 73. Since the operation of the relay 13 has opened the actuating circuit of the slow releasing relay 26, this last named relay after a short interval retracts its armatures. This is effective to connect the register sender to the calling end of the cord circuit. The release of the relay 26 is also effective to advance the register controller switch into position 10 over a circuit from ground at the innermost armature and back contact of relay 26, lowermost armature and from contact of relay 13, lowermost front contact and armature of relay 29, conductor 69, selector brush 68, controller brush 47 in its ninth position, right hand front contact and armature of relay 48, back contact, armature and winding of motor magnet 49 to grounded battery. With the operation of the relay 13, the locking circuit for the office relay 24 which has been controlled at the lowermost back contact of relay 13 is opened, causing the operated office relay to release. Relay 13 at its inner back contact and armature also opens the circuit which has been holding the relay 12, so that this last named relay releases and extinguishes the supervisory lamp 9, which has been dimly lighted to indicate to the operator that her telephone set has been in connection with the cord circuit now in use. The release of the relay 12 in turn opens the circuit of the slow releasing relay 15, which likewise retracts its armatures to disconnect the operator's telephone set from the cord circuit that is being described.

35 At this time relay 11 also deenergizes to restore the common relay 10 to common use in connection with the so-called operation of "advance plugging in". The relays 20 and 29 are held operated after the release of the relay 12 by a circuit completed from grounded battery, resistance, left hand armature and front contact of relay 7, inner left hand armature and front contact of relay 20, winding of this relay to ground and in multiple with this last described circuit, relay 29 is held operated over conductor 30, winding of relay 29 its continuity spring and armature to ground. At this time a circuit is closed over the ring side of the selected trunk, from grounded battery through both windings in series of relay 78 of Fig. 3, controller brush 50 in its tenth position, conductor 79, selector brush 80, middle armature and back contact of relay 26, inner, upper, front contact and armature of relay 29, ring

contacts of the plug and jack over the ring side of the selected trunk, middle armature and back contact of relay 81, through the lower winding of the repeating coil and 5 through both the low and the high resistance windings of relay 82 to ground. The relay 78 will not operate in series with the high resistance winding of the relay 82, which may be 10,000 ohms, but the relay 82 10 is operated and completes a circuit for operating the slow releasing relay 83. With relay 83 operated the incoming lamp 84 is lighted to signal the operator that a call is waiting at her position. The operator 15 now depresses an assignment key 85 and thereafter the number recorded on the register of the originating office, is transferred to the indicator of the wanted office, such as shown in the lower part of Fig. 2. The depression of the assignment key 85, closes a circuit from ground through the upper winding of relay 81, conductor 86, receiver controller brush 87, back contact, armature and winding of the motor magnet 88 to grounded battery. The operation of the 20 relay 81, closes a locking circuit for itself from ground at the upper armature and back contact of relay 89, innermost lower armature and front contact of relay 81, winding of this relay, conductor 90, winding of relay 91, release key 92 to grounded battery. This same locking circuit is extended in 25 multiple through the guard lamp 93 for the purpose of giving a visual indication that the selected trunk circuit is connected to the common indicator equipment. The use of such a lamp, of course, is optional.

The release key 92 permits the B operator 30 to disconnect the trunk circuit from the common receiving apparatus in case she presses the wrong assignment key. Also by operating this common key when she has memorized the number before inserting the calling plug 94 into the multiple of the wanted line, the operation of the equipment at her position is effected more quickly. An overlapping 35 operation is thereby effected to allow the operator to depress the assignment key of a second trunk when she is plugging into the multiple jack of the wanted line and operating the master key. However, without operating the release key 92, a succeeding call cannot be proceeded with until the calling plug of the first trunk has been inserted 40 into a jack such as that of the called line or a busy-back jack. The relay 81 at its lowermost armature and front contact closes a holding circuit for the relay 83, independently, of the control of relay 82, since this last 45 named relay deenergizes when relay 81 operates. The incoming lamp 84 therefore remains lighted. The relay 91 is operated in the previously described circuit and closes a circuit for the motor magnet 88, for advancing 50 the controller switch into position 2. In this position a circuit is closed for the relay 78 of Fig. 3, which may be traced through the high and low resistance windings of relay 78, controller brush 50 in its tenth position, conductor 79, brush 80, middle armature and back contact of relay 26, inner upper front contact and armature of relay 29, ring contacts of the plug and jack, conductor 97, receiver controller brush 98, the low resistance winding of relay 95 to ground. The 55 relay 95 fails to operate in this circuit, but the relay 78 of Fig. 3 does operate and at its left hand armature and front contact completes a circuit for the motor magnet 49 through controller brush 47 in position 10, 60 for moving the register controller into position 11. In this position sufficient current flows through the low winding of relay 78 to hold it operated and sufficient current passes through the winding of relay 95 to cause its 65 operation, the result is that a circuit is closed through the armature and front contact of relay 95, receiver controller brush 99 in its second position for operating the motor magnet 88. This effects the advance of the receiver controller into position 3. The high and low resistance windings of relay 95 are 70 thereby connected in series with the low resistance winding of relay 78, which causes relay 78 to deenergize, but maintains relay 95 operated. As soon as relay 78 deenergizes a circuit is closed through its armature and back contact, controller brush 47 in position 75 100 and the remainder of the circuit, previously described for actuating the motor magnet 49, whereby the brushes of the register controller are advanced to position 12. In this position the low and the high resistance windings of relay 100 are connected over the signaling circuit including the conductor 79 and since the relay 95 of Fig. 2, included 80 in series with this circuit, is connected to ground, it deenergizes and advances the receiver controller switch into position 4. The circuit is thereupon closed from grounded battery through the low resistance winding of relay 96, controller brush 98 in its fourth position, conductor 97 and thence over the circuit previously described, including conductor 79 of Fig. 3, controller brush 50 in 85 position 12 and both windings of relay 100 in series to ground. Relay 100 is operated and relay 96 remains inactive. The operation of the relay 100 closes a circuit through its armature and front contact, controller brush 47 in its twelfth position and thence over the remainder of the circuit previously described, through the motor magnet 49, for advancing the register switch into position 90 110 115 120 125 130 135 140 145 150 155 160 165 170 175 180 185 190 195 200 205 210 215 220 225 230 235 240 245 250 255 net 88, which advances the receiver controller switch into position 5. In this position the high resistance winding of relay 96 is included in this circuit with the low resistance winding 100 in Fig. 3, which causes this last named relay to release, at which time a circuit is closed from ground at its armature and back contact, controller brush 47, in its thirteenth position and thence 5 through the remainder of the previously described circuit, through the motor magnet 49 to grounded battery. This advances the register controller into position 14, which completes a circuit from battery through the 10 high and low resistance windings of relay 78 over trunk R and thence through the windings of relay 96 to battery so that relay 96 deenergizes. Relay 96 on deenergization moves the receiver switch into position 15 19. 20.

From the foregoing it will be seen that the relays 78 and 100 of Fig. 3 and the relays 95 and 96 of Fig. 2 are actuated through a series of operations, whereby the register 25 switch of Fig. 3 is first advanced and then the receiver switch of Fig. 2, is advanced. In other words the receiver switch first prepares a circuit for advancing the register switch and then the advance of the register 30 switch completes a circuit for advancing the receiver switch. This alternate operation of the two switches continues until the register switch reaches position 27 and the receiver switch reaches position 19. In these 35 positions a circuit is completed from ground through the high and low resistance windings of relay 95 and through the low resistance winding of the relay 78, for the last time so that relay 78 deenergizes and moves 40 the register switch to position 28, after which relay 95 releases and moves the receiver switch to position 20.

When the register control brush 49 reaches position 28 it closes a circuit from ground over conductor 101, left hand armature and front contact of relay 48, selector brush 102, through the outermost front contact and armature of relay 20, which is effective to short circuit the relays 20 and 29. The relay 20 is slow releasing and retracts its armatures more slowly than the relay 29 and thereby prevents the locking in operative condition of the relay 29. When the relay 20 deenergizes it opens at its inner right hand front contact and armature the circuit which has been holding the relay 48 operated. Relay 48 then deenergizes and completes a circuit from grounded battery, winding, armature and back contact of motor magnet 49, right hand back contact and armature of relay 48, back contact and armature of this relay, conductor 101 and brush 49 to ground. This circuit advances the register control switch into its normal position. 55

While the register controller switch is passing through its eighteen positions from position 10 to 27 inclusive, as above described, it connects the tip side of the trunk to conductor 53 of Fig. 1 and the conductor 70 42 and brush 41 of Fig. 3, to the eighteen register relays, shown in the upper left hand corner of Fig. 3. The brush 103 of the receiver switch of Fig. 2, in passing through its eighteen positions from 2 to 19 inclusive, 75 in synchronism with the register controller switch extends the tip side of the trunk to the eighteen call indicator relays, shown in the lower right hand corner of Fig. 2. In this progressive advancing of the register controller and the receiver switch, relays in the receiver switch circuit corresponding to the operated relays of the register sender are operated and locked. 80

It should be noted that the lamp indicator 85 relays and the contacts of the register relays are alternately connected to ground and battery in order that the overlap, when the register controller switch moves to a succeeding position, will not falsely operate the indicator 90 relays at the distant office represented at Fig. 2. The called number was assumed to be #4468 and it will be remembered from the preceding description that the thousands 95 register relay 36, the hundreds register relay 36^A, the tens register relays 33^B and 35^B and the units register relays 33^C, 34^C and 35^C were operated. The thousands indicator relay 104 is therefore operated, as well as the hundreds relay 105, the tens relays 106 and 107 100 and the units relays 110, 111 and 112 are likewise operated and locked over conductors 114 and 123. It will thus be seen that the #4 thousands lamp is lighted in a circuit, which may be traced from grounded 105 battery, lamp #4, back contact and armature of relay 111, uppermost armature and front contact of relay 104, uppermost back contact and armature of relay 112, to ground. In Fig. 2 the indicator lamps for the thousands indicator only are shown, since the 110 lamps for the hundreds, tens and units indicators are wired in the same manner as those of the thousands lamps. The circuit of the #4 thousands lamps, has been traced and it 115 will be understood that the circuit for the #4 hundreds lamp is similar to that of the thousands lamp. With the tens relays 106 and 107 operated, a circuit is closed for lighting the tens lamp #6 while with the 120 units relays 110, 111 and 112 a circuit is closed for lighting the units lamp #8 only. Since the stations relay 72 has been operated, the corresponding stations relay 113 of Fig. 2, is operated and locked over conductor 125 114 to light the stations lamp 115.

The B operator now inserts the calling plug 94 into a multiple jack of the called line. This is effective to energize the slow releasing relay 89 in a circuit closed from 130

grounded battery, winding of this relay, innermost back contact and armature of relay 116, conductor 117, sleeve contacts of the plug 94 and the jack of the called line, winding of relay 118 to ground. The operation of relay 89 opens the circuit which has been holding the relay 81 locked, so that this relay deenergizes to disconnect the signaling conductors from the tip and ring conductors of the trunk and at its armatures and back contacts closes break points in the tip and ring conductors of the trunk. When relay 81 deenergizes it opens the circuit of relay 91, shown in the lower left hand corner of Fig. 2 and this last named relay retracts its armatures to close a circuit through receiver brush 87 for advancing the receiver into its normal position. The release of the relay 91 also unlocks all of the indicator relays of Fig. 2 that have been operated. As soon as the mentioned break points are closed in the tip and ring conductors of the trunk, relay 119, shown near the top of Fig. 1 has its circuit closed in series with the two left hand windings of the repeating coil and the windings of relay 82 and relay 120. Relay 119 will not operate in series with the high resistance winding of relay 82 but when the called party answers, this high resistance winding is short circuited, which permits relay 119 to operate for the purpose of giving supervision at the originating office.

The B operator at the distant office after connecting the plug 94 to the called telephone line, depresses the ringing key 122 to select the proper frequency for signaling the wanted station on line 2 as indicated by the station lamp 115. The depression of the ringing key 122 effects the operation of the slow releasing relay 121, which in turn closes a circuit from ground through the meter relay, inner armature and front contact of relay 121, conductor 130, lowermost armature and front contact of relay 89, upper winding of relay 116 to grounded battery. Relay 116 in operation closes a locking circuit for itself through its lower winding, its inner front contact and armature, conductor 117 to ground through relay 118. The relay 126 is also operated at this time from grounded battery, resistance, its winding, lowermost front contact and armature of relay 89, conductor 130 to ground through the meter relay. Relay 128 is likewise actuated at this time in a circuit which may be traced from grounded battery, winding of relay 128, middle front contact and armature of relay 89, conductor 131, outer front contact and armature of relay 121 to ground. With relays 126 and 128 operated, 66 cycle ringing current is applied through the inner back contact and armature of relay 127, front contacts and armatures of relays 128 and 83, winding of the trip relay 125 through the inner front contact and armature of relay 126, through the ring contacts of the plug 94, and multiple jack of the called line over the lower side of this line and through the bell at the wanted substation, which is assumed to be that shown in detail in Fig. 2 over the upper side of the called line, tip contacts of the jack and plug, upper armature and front contact of relay 126 to ground. Ringing current is applied over this circuit until the called party responds, at which time the trip relay 125 is energized and at its front contact and armature closes a circuit by which the ringing relay 126 is shunted, causing it to retract its armatures. At this time the supervisory relay 129 is energized in a circuit completed over the two sides of the called end of the cord circuit and the called line in series. At the lower armature and front contact of this relay, the high resistance winding of relay 82 is short-circuited, so that the supervisory relay 119 of Fig. 1, is now operated. The operation of relay 119 at its right hand armature and front contact closes a circuit to operate the relay 124, which relay is locked operated through its left hand front contact and armature, lowermost front contact and armature of relay 13, innermost back contact and armature of relay 126 to ground. All of the supervisory lamps of Figures 1 and 2, are now extinguished.

When the calling subscriber terminates the call by replacing his receiver on its switchhook, the answering supervisory relay 8 deenergizes and causes the supervisory lamp 9 to be lighted in a circuit closed through the inner left hand armature and back contact of this relay, right hand armature and front contact of relay 7 through the impedance coil to ground. This is a signal to the A operator that the connection may be disestablished, whereupon she removes the answering plug 5 and the calling plug of this cord circuit from the jacks with which they have been in engagement.

If the called subscriber terminates the connection, the supervisory relay 129 deenergizes and removes the short-circuit from about the high resistance winding of relay 82 and when this high resistance winding is again included in series with the relay 119 of Fig. 1, it causes this last named relay to deenergize, whereupon the supervisory lamp 132 is lighted from grounded battery, right hand armature and front contact of relay 124, back contact and armature of relay 119 to ground. This is also a signal to the A operator to disestablish the connection, which she does by removing the plugs from the jacks with which they have been in engagement. At the B operator's position when the supervisory relay 129 deenergizes, the supervisory lamp 84 is

lighted in a circuit closed through the lower armature and front contact of relay 116, back contact and armature of relays 83 and 129 to ground. The lighting 5 of the lamp 84 is also a signal to the B operator to disestablish the connection by removing the plug 94 from the called jack.

What I claim is:

1. In a telephone system, a plurality of 10 telephone lines, a link circuit for use in interconnecting said telephone lines, line designation recording means at said link circuit including a plurality of selectively and 15 variably operable devices in which several portions of a line designation are recorded, means including a single pair of manually 20 operated contacts for selectively operating said devices in response to a single connection between said pair of contacts, and means for maintaining said devices in their 25 operated condition after said connection is broken.

2. In a telephone system, a plurality of 30 offices, telephone lines terminating at each 35 of said offices, link circuits for interconnecting said offices, means for connecting a telephone line to one end of one of said link circuits, and means for connecting the other end of said link circuit to another telephone 40 line, a recording device at one of said offices, 45 said recording device including a plurality of selectively and variably operable mechanisms, a signaling device at the other of said offices arranged to be variably operated 50 under the control of said recording device to indicate the number of the wanted line, and means including a single pair of manually 55 controlled contacts for selectively operating several mechanisms of said recording 60 device, in response to a single actuation of said pair of contacts.

3. In a telephone system, a plurality of 65 telephone lines, a plurality of link circuits, each of which may be used for interconnecting 70 said telephone lines, a plurality of register senders common to said link circuits, each register sender including a plurality of selectively and variably operable registers, means for associating an idle register sender 75 with a link circuit taken for use, and means including a single pair of contacts for operating the registers of a selected register sender in response to a single actuation of 80 said pair of contacts.

4. In a telephone system, a plurality of 85 telephone lines, a link circuit for use in interconnecting said telephone lines, a manually operable switch having contacts for extending said link circuit in the direction 90 of a telephone line, a register sender having a plurality of variably operable registers, and means including a single pair of manually 95 operated contacts for selectively operating said registers in response to a single operation of said pair of contacts, said sin-

gle pair of contacts including one contact of said manual switch.

5. In a telephone system, a plurality of 100 telephone lines, a link circuit for use in interconnecting said telephone lines, said link circuit terminating at one end in a manual switch, a register sender provided with a plurality of variably operable registers associated with said link circuit, a contact for each of the telephone lines of a group of 105 said lines, and means including a contact of said manual switch and the individual contact of the wanted telephone line for selectively operating the registers of said register sender in accordance with the designation 110 of the wanted telephone line.

6. In a telephone system, a plurality of 115 telephone lines, a link circuit connectable to a wanted telephone line, a cord circuit provided with a manual switch for extending 120 a calling telephone line to the other end of said link circuit, an indicator device at said link circuit, a register sender arranged to be associated with a cord circuit, said register sender being provided with a plurality of 125 registers for selectively operating said indicating device, and means including a contact individual to a wanted telephone line and a contact of the manual switch of said cord circuit for selectively operating said registers.

7. In a telephone system, a plurality of 130 telephone lines, a link circuit for interconnecting said telephone lines, a register sender having a plurality of registers arranged to 135 be associated with said link circuit, a code machine common to a plurality of telephone lines for selectively and variably actuating the registers of a register sender, and means responsive to a single actuation of a single 140 pair of terminals for controlling the setting of said registers by said code machine.

8. In a telephone system, telephone lines, a link circuit for interconnecting said telephone lines, a register sender provided with 145 a plurality of registers, a code impulse machine common to a plurality of telephone lines, means including a sequence device for placing the registers of a sender successively 150 under the control of said code impulse machine, and means including a single pair of manually operated contacts for controlling 155 said registers from said impulse machine.

9. In a telephone system, a plurality of 160 telephone lines, a link circuit for use in interconnecting said telephone lines, a register sender provided with a plurality of variably 165 operable registers connectable to said link circuit, an individual contact for each of certain of said telephone lines, and means 170 cooperating with the individual contacts of a wanted telephone line for selectively operating the registers of said register sender in accordance with the designation of the 175 wanted telephone line.

10. In a telephone system, a plurality of telephone lines, link circuits for use in interconnecting said telephone lines, a plurality of register senders each provided with a plurality of variably operable registers, means for connecting an idle register sender to a link circuit taken for use in interconnecting said telephone lines, an individual contact for each of certain of said telephone lines, and means including the individual contact of the wanted telephone line for selectively operating the registers of said connected register sender in accordance with the designation of the wanted telephone line.
15. 11. In a telephone system, a plurality of telephone lines, a plurality of link circuits for use in interconnecting said telephone lines, means for extending said link circuits to said telephone lines when they originate calls, an operator's telephone set, automatic means for connecting in succession said operator's telephone set to extended link circuits, means for indicating to which link circuit an operator's telephone set is connected, a plurality of register senders each provided with a plurality of variably operable registers, means for connecting an idle register sender to the link circuit to which said operator's telephone set is connected, an individual contact for each of
- 20
- 25
- 30
- certain of said telephone lines, and means including the individual contact of the wanted telephone line for selectively operating the registers of said connected register sender in accordance with the designation of the wanted telephone line.
- 35
12. In a telephone system, a plurality of telephone lines, a plurality of link circuits, means for extending said link circuits to telephone lines contemporaneously originating calls, an operator's telephone set, automatic means for connecting said operator's telephone set to said last mentioned link circuits one at a time, a plurality of register senders each provided with a plurality of variably operable registers, means for connecting an idle register sender to an extended link circuit, an individual contact for each of certain of said telephone lines, and means including the individual contact of the wanted telephone line for operating selectively in accordance with the designation of the wanted telephone line, the registers of the register sender connected to the link circuit associated with said operator's telephone set.
